UNITED STATES PATENT OFFICE.

JOHN H. STILLWAGGON, OF RICHMOND HILL, NEW YORK.

FIRE-HOSE SUPPORT.

1,344,736.

Specification of Letters Patent. Patented June 29, 1920.

Application filed July 13, 1915. Serial No. 39,542.

To all whom it may concern:

Be it known that I, JOHN H. STILLWAGGON, a citizen of the United States, residing at Richmond Hill, in the county of Queens 5 and State of New York, have invented certain new and useful Improvements in Fire-Hose Supports, of which the following is a specification.

This invention relates to hose supports 10 for fire hose and the like, adapted to support a hose and its nozzle in compacted and substantially coiled condition, and which, in cases of emergency, may be operated to precipitate the hose to the floor in automatically uncoiled condition, ready for use. 15 To this end the invention includes a plurality of hose-supporting fingers loosely pivoted on a rod or the like support, and slideable along the same, together with a pivoted member adapted to support the free ends of said hose-supporting fingers and to be held in such supporting position by means of the nozzle of the hose, the pivoted support for the free ends of the fingers tilting 20 under the weight of the hose when the nozzle is removed from such locking position.

One of the objects of the invention is to provide a device having the general characteristics mentioned above, which is extremely simple in its construction and therefore cheap to manufacture, while it is very certain in operation.

Another object is to provide an improved form of nozzle-controlled lock for the pivotal support for the free ends of the hose-supporting fingers.

Other objects and aims of the invention, more or less broad than those stated above, 40 together with the advantages inherent, will be in part obvious and in part specifically referred to in the course of the following description of the elements, combinations, arrangements of parts, and applications of principles constituting the invention; and 45 the scope of protection contemplated will appear from the claims.

In the accompanying drawings, which are to be taken as part of this specification, 50 and in which I have shown merely a preferred form of embodiment of the invention, Figure 1 is an elevation of a device embodying my invention, with parts broken away; Fig. 2 is a top plan view of the 55 same; Fig. 3 is a section on the line 3-3 of Fig. 2 showing the parts in normal posi-

tion with the hose nozzle in place; and Fig. 4 is a view similar to Fig. 3 but with the hose nozzle removed and showing the position of the parts under such conditions. 60

Referring to the numerals on the drawings there is shown at 5 a generally rectangular oblong frame which may be pivotally supported from a wall bracket 6 so that it can swing horizontally. A supporting rod 7 is secured in the end walls of the frame adjacent one of the side walls, and on this supporting rod 7 is loosely pivoted a plurality of hose-supporting fingers 8, which may be very cheaply made from stiff wire 70 or the like, having one end bent into an eye which encircles the rod 7. Also pivoted in the end walls of the frame as at 9, is a shelf 10, which is adapted to support the free ends of the hose-supporting fingers 8. This pivoted or tilting shelf 10 has a finger 11 extending transversely from one end thereof, which finger has a beveled face 12. Secured to the outer end of the frame is a pair of fingers 14 provided at their outer ends with 80 slightly raised portions 15. These fingers 14 are separated sufficiently to allow of the introduction between them of the end of a hose nozzle 16, whose flaring mouth, as shown in Fig. 2, rests against the fingers 85 14, and is prevented from accidentally sliding off from said fingers by means of the raised portions 15. The hose nozzle is utilized as a means for keeping the tilting platform or shelf 10 in the Fig. 2 position 90 by means of a latch-piece 17 pivoted on the underside of and at one end of one of the fingers 14, so that it may swing in a horizontal plane, a slot 18 being provided in the end wall of the frame, through which the 95 free end of said latch-piece extends.

The hose is looped over the fingers 8 in the ordinary way and as indicated in Figs. 1 and 2, and may be very closely packed, because of the fact that the fingers may be 100 slid along the supporting rod 7 and tilting platform 10. When the hose is all in place on the fingers, with the latch-piece 17 in the position of Fig. 3, that is, under the beveled face 12 of the finger 11, it is evident 105 that the nozzle 16, in the position of Figs. 2 and 3, will hold the free end of the latch-piece under the beveled face 12 of the finger 11, thus keeping the tilting platform in the Fig. 2 position. If, however, the hose nozzle 110 is lifted out of its seat in the fingers 14 and withdrawn from between them, the weight

of the hose pressing down on the platform 10 will cause the finger 11, on account of the bevel 12, to push the latch-piece 17 to the dotted line position of Fig. 2, or the 5 full line position of Fig. 4, thus permitting the finger 11 and platform 10 to swing downwardly, and allowing the several fingers 8 to move to the position which is indicated in Fig. 4, the hose of course slipping off and 10 dropping to the floor, ready for use.

Inasmuch as many changes could be made in the above construction, and many apparently widely different embodiments of my invention could be made without departing 15 from the scope thereof, it is intended that all matter contained in the above description or shown in the accompanying drawings shall be interpreted as illustrative and not in a limiting sense.

20 It is also to be understood that the language used in the following claims is intended to cover all the generic and specific features of the invention herein described and all statements of the scope of the invention which, as a matter of language, might 25 be said to fall therebetween.

I claim:

1. In a device of the kind described, a 30 frame, a hose-supporting finger pivoted to swing around a horizontal axis at one side of the frame, a tilting platform pivoted to move around a horizontal axis at the other side of the frame and adapted to support the free end of said hose-supporting finger, 35 a projection on said platform, a latch member pivoted to swing around a vertical axis, the free end of said latch member engaging the end of said projection to hold the platform in position to support the end of the 40 hose-supporting finger, and means for supporting a nozzle in such position that it will maintain the latch member in engagement with said projection.

2. In a device of the kind described, a 45 frame provided with nozzle supporting fingers, a plurality of hose-supporting fingers pivoted to swing about a horizontal axis at one side of the frame, and an elongated platform pivoted on a longitudinal axis to 50 the frame, the platform being pivotally movable to two positions, in the first of which it supports the free ends of the hose supporting fingers, and a latch member secured to one of the nozzle supporting fingers 55 movable to two positions, in the first of which it maintains the platform in its finger-supporting position, while in the second position of the latch the platform is free to turn to its second position and release the 60 ends of the hose supporting fingers.

3. In a device of the kind described, a frame provided with nozzle supporting fingers, a plurality of hose-supporting fingers pivoted to swing about a horizontal axis at one side of the frame, and an elongated platform pivoted on a longitudinal axis to the frame, the platform being pivotally movable to two positions, in the first of which it supports the free ends of the hose supporting fingers, and a latch member secured to one 65 of the nozzle supporting fingers movable to two positions, in the first of which it maintains the platform in its finger-supporting position, while in the second position of the latch the platform is free to turn to its 70 second position and release the ends of the fingers, and a nozzle on its supporting fingers co-operating with said latch member for holding the latch in its first position to keep the platform in finger-supporting position. 75

4. In a device of the kind described, a frame provided with nozzle supporting fingers, a plurality of hose-supporting fingers pivoted to swing about a horizontal axis at one side of the frame, an elongated platform pivoted on a longitudinal axis to the frame, the platform being pivotally movable to two positions, in the first of which it supports the free ends of the hose supporting fingers, and a movable latch secured to 90 one of the nozzle supporting fingers for holding the platform in said first position.

5. In a device of the kind described, a frame provided with a slot, a plurality of hose-supporting fingers pivoted to swing 95 about a horizontal axis at one side of the frame, an elongated platform pivoted on a longitudinal axis to the frame, the platform being pivotally movable to two positions, in the first of which it supports the free 100 ends of the fingers, and a movable latch arranged to swing in a horizontal plane for holding the platform in said first position, the free end of the latch passing through said slot in its movement engaging the platform to retain the platform in the said first or finger-supporting position.

6. In a device of the kind described, a frame, a hose supporting finger pivoted to swing around a horizontal axis at one side 110 of the frame, a tilting platform pivoted to move around a horizontal axis at the other side of the frame and adapted to support the free end of said hose supporting finger and a nozzle support provided with means 115 for engaging the platform to hold the platform in finger supporting position.

In testimony whereof I affix my signature.

JOHN H. STILLWAGGON.
